UNITED STATES PATENT OFFICE.

FERDINAND H. YOUNG, OF CHICAGO, ILLINOIS, ASSIGNOR TO THE ABBOTT LABORATORIES, OF CHICAGO, ILLINOIS, A CORPORATION OF ILLINOIS.

SOLUTION OF DI-CHLORAMINE-T.

No Drawing.

Application filed December 31, 1919. Serial No. 348,666.

To all whom it may concern:

Be it known that I, FERDINAND H. YOUNG, a citizen of the United States, residing at Chicago, in the county of Cook and State of Illinois, have invented certain new and useful Improvements in Solutions of Di-Chloramine-T, of which the following is a specification.

Di-chloramine-T is a germicide or anti-septic used for many purposes and particularly for spraying on wounds. This material, which heretofore has been furnished in powdered crystalline form, or in the form of tablets, is oil-soluble, and is dissolved in a relatively inexpensive solvent, such as chlorcosane, theoretically, just before it is to be used, the reason of course being that when dichloramine-T is made up into such a solution, it will rapidly degenerate or deteriorate, lose strength, and become unfit for use. Unfortunately, however, the Di-chloramine-T does not dissolve quickly, and the time taken to dissolve same may, in some cases, mean the difference between life and death; while, on the other hand, if an attempt be made to hasten the process by heating, the solution may be ruined by the high temperature employed. Owing to the above difficulties, there is often a strong temptation on the part of the physician to make up a comparatively large batch of such solution in the hope that it will all be used before any substantial deterioration occurs, with the inevitable result that sooner or later some of the left over stale solution is used, the desired effect is not secured, the patient suffers and the manufacturer unjustly receives blame for furnishing an inferior article.

In applying my invention to the specific case cited, I made numerous tests and experiments in the effort to discover some way of producing a strong liquor or preliminary solution of dichloramine-T, the solvent or vehicle of which would have no effect upon

the dichloramine-T when in solution and which would not affect the efficacy of the germicide when diluted with chlorcosane. Monochlorbenzene and o-dichlorbenzene, I have discovered can successfully be employed in which to dissolve the solid powder or crystals of dichloramine-T. Such a solution of dichloramine-T in either of the said liquids, is permanent for all practical purposes, when kept under ordinary conditions; and, furthermore, neither of the liquids has any undesirable effect upon the ultimate solution as used. Obviously, the advantages of being able to take a few drops of the strong dichloramine-T liquor and dilute it with the required amount of chlorcosane, over the laborious dissolving of the solid in the chlorcosane, are numerous, it being merely necessary to stir up the solution for a second or two, whereupon the germicide is ready for use.

The making up of such a germicide solution according to my invention is so rapid, easy, and convenient, that the user is not subjected to the temptation of trying to hasten the process by heat, nor will he be likely to use a left-over or stale solution.

I claim—

1. The improvement in the art of preparing a solution of dichloramine-T, which consists in first dissolving the solid material in a chlorinated benzene with which it will not deteriorate, and subsequently incorporating a portion of the concentrated liquor with the desired quantity of chlorcosane.

2. The improvement in the art of preparing an ultimate solution of dichloramine-T in chlorcosane, which consists in first dissolving the dichloramine-T in monochlorbenzene, and subsequently, when required for use, diluting a portion of the concentrated liquor with the required amount of chlorcosane.

FERDINAND H. YOUNG.
